UNITED STATES PATENT OFFICE.

EARL H. SHERBONDY, OF CLEVELAND, OHIO, ASSIGNOR OF ONE-HALF TO WILLIAM E. SHERBONDY, OF CLEVELAND, OHIO.

EXPLOSIVE-ENGINE.

988,514.

Specification of Letters Patent. Patented Apr. 4, 1911.

Application filed September 21, 1908. Serial No. 454,076.

To all whom it may concern:

Be it known that I, EARL H. SHERBONDY, a citizen of the United States, resident of Cleveland, county of Cuyahoga, and State of Ohio, **6** have invented a new and useful Improvement in Explosive-Engines, of which the following is a specification, the principle of the invention being herein explained and the best mode in which I have contemplated **10** applying that principle, so as to distinguish it from other inventions.

My present invention relating as indicated to explosive motors, has more particular regard to explosive gas engines of the **15** two cycle type of construction, but as will be evident from further description of said invention, various features thereof are equally adaptable to use in connection with various forms of motors of the general class **20** in hand.

The object of the invention is to provide an explosive motor of simple and compact construction, and one possessing increased efficiency over prevailing constructions, such **25** efficiency being secured both by improving the control of the admission of the fuel to the explosive chamber of the engine, and by regulating the fuel supply.

To the accomplishment of the above and **30** related ends said invention then consists of the means hereinafter fully described, and particularly pointed out in claims.

The annexed drawings and the following description set forth in detail certain mechanism embodying the invention, such disclosed means constituting, however, but one of various mechanical forms in which the principle of the invention may be used.

In said annexed drawings:—Figure 1 is **40** a part side elevation and part section of a two cylinder, two cycle gas engine, embodying my several improvements; Fig. 2 is a transverse section with parts shown in elevation of one cylinder in said engine, the **45** plane of the section being indicated by the line 2—2, Fig. 1; Fig. 3 is a transverse section of the fuel supply control mechanism and appurtenant parts, the plane of such section being indicated by the line 3—3, Fig. **50** 1; Fig. 4 is a plan view of the engine, a part of the control mechanism of Fig. 3 being shown in section; Fig. 5 is a horizontal section of one of the cylinders taken on the line 5—5 Figs. 1 and 2; Fig. 6 is a similar horizontal section taken on the line 6—6 Figs.

1 and 2; Fig. 7 is a horizontal section of the control mechanism of Fig. 3 taken on plane indicated by line 7—7 on said Fig. 3; Figs. 8 and 9 are similar sectional views of such control mechanism taken on planes indicated by the lines 8—8 and 9—9 of the same figure; and Figs. 10 and 11 are vertical sectional views of a detail of the cylinder and piston showing the same in different co-operating positions. **65**

The engine illustrated in general assembled view in Figs. 1 and 2, will be seen to comprise a base A upon which is secured the crank case A', which latter in turn is surmounted by the cylinders A², such cylinders as usual in gas engine construction including a removable cap portion A³. The engine being as indicated of the two cycle type, the crank case, as is general in this type of engine, is utilized as a compression chamber, and to **70** this end is separated into two chambers a—a corresponding with the cylinders A² A², respectively, by means of end bearings a' and middle bearings a² wherein is journaled the crank shaft A⁴. Connected with said crank shaft, by means of suitable connecting rods **75** b, are hollow cylindrical pistons B respectively held in cylinders A². It being with details in the construction of such pistons B and the co-operating portion of the cylinders, and with the mechanism for controlling the supply of fuel to the crank cases a, that the present invention is chiefly concerned, these **80** features will be taken up in the order named. **85**

That portion a² of each cylinder within **90** which the charge is fired, is cast hollow, and suitable inlet connections a' and outlet connections a² for maintaining a circulation of water or like cooling liquid therethrough are provided as usual. For transferring the **95** charge from the crank case a constituting, as stated, the compression chamber of a cylinder, to the explosion chamber a² of such cylinder, I simply utilize a selected portion a³ of the hollow cooling chamber, such portion being suitably separated from the remainder of the chamber, as will be readily understood. I am thus enabled to do away with the necessity for exterior connections for conducting the charge from the compression chamber to the explosion chamber. Similarly, a portion a² of the same cooling chamber is set off and connected with the exhaust A⁵, for conducting the spent gases **100** from explosion chamber a². The corre- **105**

sponding hollow cylindrical piston B is formed with ports b' adapted to register with the lower opening of connecting chamber a⁶ in the lower position of the piston as illustrated in Figs. 1 and 2. At approximately the same time that such position is assumed, the port into exhaust chamber a⁷ and the upper opening of connecting chamber a⁶ are uncovered. I so arrange, however, 10 the upper and lower openings of said chamber a⁶ in relation to the piston, that the port b' in the latter uncovers the lower chamber opening before the upper opening is uncovered. See Fig. 10. By this means the 15 charge, under its full initial compression, is admitted into the chamber a⁶, whence it is ready to rush into the explosion chamber a³ just as soon as the opportunity presents, there being thus no possibility presented for such 20 chamber to be filled with the waste gases from the explosion chamber. When such gases are admitted, their course is determined, so as to most effectually secure the necessary scavenging of the explosion chamber 25 without wasting the charge, by means of the novel construction of the deflector plate B' which I use upon my piston. This deflector, which for convenience in construction, will ordinarily be cast separate from 30 the piston and then secured thereto, is in the form of a half-annulus with a curved outer face, and a substantially vertical inner face, Figs. 10 and 11, although the form of the latter is immaterial. Its respective ends 35 moreover are provided with lateral portions b² inclosing more or less the outer face, Fig. 1. This outer face comprises a sharply offset portion b³ to the face of the piston. Such face portion b³ is only a trifle removed 40 from the inner face of the cylinder, and is inclined outwardly and toward the same, so that when the upper opening of the chamber a⁶ leading from the crank case is first uncovered, the gases forming the charge, which 45 will at this time be under the greatest pressure, are deflected upwardly at a sharp angle such that they will hug the cylinder walls, and strike the curved inner face of the cylinder cap A². The continued downward 50 movement of the piston opens the port more and more widely, and as the charge under continually decreasing pressure is thus more freely admitted, it strikes the curved portion b⁴ of the face of the deflector, such curve 55 being calculated so to deflect the charge, following the initial admission thereof, as to completely fill the explosion chamber without intercepting or pocketing any portion of the waste gases. The jet first admitted, and 60 thus sharply deflected upwardly as described, obviously will travel in advance of the larger volume subsequently admitted; the last jets in fact never reach the farther wall of the expanding chamber. The result of this construction is obviously a much more thorough 65

scavenging of the chamber than is obtainable where the prevailing construction of deflector plate is employed, and if the exhaust port be properly disposed and movement of the piston correctly timed, very little of the charge need be wasted. 70

Located intermediately between the two engine cylinders A² upon a laterally projecting portion of the crank case A' is a vertically disposed cylindrical casing C, the lower end of which is provided with two ports c c respectively leading into the compression chambers a a in such crank case. Intermediately of its ends, this casing is surrounded by two annular chambers C' C² 80 separated from each other, but both having an annular series of ports respectively designated c' c² communicate with the interior of the casing. The upper C' of said chambers, which is the larger of the two, communicates directly with the atmosphere through an opening c³, and is designed to supply the necessary amount of air for forming the charge; while the lower chamber C² is connected with a suitable gas supply pipe c⁴ for supplying the gas or equivalent fuel for such charge. 85

Extending longitudinally of the casing is a shaft C³ the lower end of which is stepped in a suitable bearing a⁸ conveniently provided in the inner face of the crank case casting. This shaft is designed to be driven directly from the crank shaft A⁴ by a gear a⁹ on the latter meshing with another gear c⁵ on the shaft. Shaft C³ bears, on line with the lower end of the casing, a rotatable cylindrical valve c¹¹ that serves to close such lower casing end, and to control communication between the interior of the casing and the respective ports c c that lead to the separated crank cases. Reciprocally mounted upon said shaft above the rotatable valve is a sleeve c⁶ to the lower end of which is secured an annular valve c⁷ adapted to control the fuel inlet port c². Movement of such inlet control valve, and thus the supply of fuel, is regulated through a governor comprising two fly-balls c⁸ carried by shaft C³ and adapted to depress the sleeve c⁶ aforesaid against an expansion spring c¹² 110 that is adjustably supported by a yoke c⁹ pivotally mounted in the casing and raised or lowered by means of a regulating nut c¹⁰, as will be readily understood. 115

The upper portion of the shaft is inclosed within a continuation D of the valve and governor casing C just described, and bears, reciprocally mounted thereon near its end, a cam d that, as the shaft rotates, alternately actuates two spring pressed plungers D' to 120 operate the ignition devices E of the respective cylinders. Such cam d is in the form of a sleeve, the cam face of which is pitched, so that as the sleeve is raised or lowered the timing of the ignition is corre- 125 130

spondingly advanced or retarded. Such raising and lowering of the sleeve is effected by means of a hollow cylindrical member D^2 rotatably secured to the upper end of the same by means of pins d' engaging helical ways d^2 in said member, so that upon rotation of the member by means of a lever d^3 , the desired adjustment of the cam is effected. This lever engages a suitable ratchet d^4 on the upper end of the casing D , whereby it is retained in any desired position.

The details of the ignition devices E need not be further noted than to observe, see Figs. 1, 2 and 4 that it is of the make and break type, the plungers D' just referred to as being reciprocated by the cam d being adjustably connected with the oscillatory element of the devices by suitable connecting rods e . The discharge pipe a^5 through which the water escapes from the cooling jacket of the cylinder, affords a convenient support for a bus-bar e' , Fig. 4, that serves to lead the current to the spark plugs e^2 of the respective ignition devices. Such bar, however, I do not connect directly with the spark plugs, but oscillatorily mount thereon switch levers e^3 that are adapted to bridge the space between the bar and the plug. Either or both cylinders it will thus be seen may be easily and conveniently cut out by simple manipulation of such switch levers.

The general cycle of operation of the engine need not be further noted than to remark that the connection of shaft C^3 is arranged to properly correlate the admission of the charge into the respective engine cylinders with the movement of the pistons therein. The intake valve, governor, and ignition devices all being actuated by this same shaft, the controlling mechanism of the engine is obviously simplified in construction and rendered correspondingly compact. Increased ease of adjustment and control, as well as economy of operation naturally follow. The further and marked economy secured by designing the outer face of the deflector on the piston with a due regard for the function which it serves, all as hereinbefore described, has been amply demonstrated by tests under practical operative conditions. It should be further explained that this result is best secured where the curve of the inner face of the cap or dome A^3 is formed to cooperate with that of deflector B' in producing the desired sweep of gases through the explosion chamber. A feature in the operation of the exhaust has been reserved for attention in this connection, such feature consisting in the creation of a slight vacuum or suction effect in chamber a^6 just at the time when, see Fig. 2, the piston approaches its lowermost position and free communication is established from inlet ports c^1 c^2

through ports c , crank-case a , piston port b' and passage a^6 with explosion chamber a^3 of the cylinder. Such suction effect is conveniently secured in the case of paired cylinders such as I here show by running the exhaust pipes A^5 of the respective cylinders together at such an angle, see Fig. 4, that the discharge of the waste gases through the one tends to produce a vacuum in the other. Other, and mechanical, means may be employed instead of this device, if so desired, but even with a slight suction effect, the compression is perceptibly increased with corresponding increase in efficiency.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In an explosive engine, the combination of a plurality of cylinders, a divided crank case, a casing located intermediately between said cylinders and having ports leading to the divisions of said crank case respectively, fuel connections for said casing, and a rotatable valve in said casing adapted to control aforesaid ports.

2. In an explosive engine, the combination of a plurality of cylinders, a divided crank case, a casing located intermediately between said cylinders and having ports leading to the divisions of said crank case respectively, a fuel inlet port, a shaft extending longitudinally of said casing, a rotatable valve borne by said shaft and adapted to control the outlet ports of said casing, and governor mechanism operated by said shaft and adapted to control the inlet port of said casing.

3. In an explosive engine, the combination of a plurality of cylinders, a divided crank case, a casing located intermediately between said cylinders and having ports leading to the divisions of said crank case respectively, a fuel inlet port, a shaft extending longitudinally of said casing and connected to be driven from the crank-shaft of said engine, a rotatable valve borne by said shaft and adapted to control the outlet ports of said casing, a reciprocable valve for controlling the fuel inlet port, and a governor operated by said shaft and adapted to reciprocate said inlet control valve.

4. In an explosive engine, the combination of a pair of cylinders, a divided crank case, a cylindrical casing located intermediately between the cylinders and having ports leading to the divisions of said crank case respectively, an annular chamber surrounding said casing, said chamber having ex-

- ternal fuel connections and being connected with said casing by an annular series of ports, a shaft extending longitudinally of said casing and connected to be driven from the crank-shaft of said engine, a rotatable cylindrical valve borne by said shaft and adapted to control the outlet ports of said casing, a sleeve reciprocally mounted on said shaft and bearing a valve adapted to control such annular series of ports, resilient means tending to raise said sleeve to open said valve, and a governor borne by said shaft and adapted to depress said sleeve to close said valve.
5. In an explosive engine, the combination of a pair of cylinders, a divided crank case, a cylindrical casing located intermediately between the cylinders and having ports leading to the divisions of said crank case respectively, an annular chamber surrounding said casing, said chamber having external fuel connections and being connected with said casing by an annular series of ports, a second chamber surrounding said casing above said first chamber, said chamber having similar ports opening into the casing interior and exterior air connections, a shaft extending longitudinally of said casing and having geared connection with the crank-shaft of said engine, a rotatable cylindrical valve borne by said shaft and adapted to control the outlet ports of said casing, a sleeve reciprocably mounted on said shaft and bearing a valve adapted to control the fuel-inlet ports, a spring tending to raise said sleeve to open said valve, and a governor borne by said shaft and adapted to depress said sleeve to close said valve.
6. In an explosive engine, the combination of a plurality of cylinders, a divided crank case, a casing located intermediately between said cylinders and having ports leading to the divisions of said crank case respectively, a fuel inlet for said casing, a shaft connected to be driven from the crank-shaft of said engine, a rotatable valve borne by said shaft and adapted to control said outlet ports, governor mechanism operated by said shaft and adapted to control said inlet port, and mechanism for operating the ignition devices of the respective cylinders, likewise operated by said shaft.
7. In an explosive engine, the combination of a pair of cylinders, a divided crank case, a cylindrical casing located intermediately between the cylinders, said casing having ports at its lower end leading to the divisions of said crank case respectively, and an intermediate fuel inlet port, a shaft extending longitudinally of said casing and connected to be driven from the crank-shaft of said engine, a rotatable valve borne by the lower end of said shaft and adapted to control the outlet ports of said casing, governor mechanism operated by said shaft for controlling said inlet port, and mechanism for operating the ignition devices of the respective cylinders borne by the upper end of said shaft.

Signed by me, this 2nd day of September, 70
1908.

EARL H. SHERBONDY.
